UNITED STATES PATENT OFFICE.

CHARLES LEA, OF MILTON, MASSACHUSETTS, ASSIGNOR TO SHAWMUT ENGINEERING COMPANY, OF BOSTON, MASSACHUSETTS, A CORPORATION OF MASSACHUSETTS.

SPOOL-RETARDING DEVICE FOR TUBE FRAMES.

Application filed April 1, 1927. Serial No. 180,152.

This invention relates to spool-retarding means for use in Axminster tube frames for the purpose of producing the necessary yielding resistance to the rotation of the yarn-spool under the pull of the unwinding yarn as the yarn is drawn off for use in the weaving operation.

Such spool-retarding means have very commonly consisted of an arm or leaf spring secured to the carrier-bar or frame of the tube frame so that its free end normally presses toward the spool head to create frictional resistance to the spool rotation, said free end having riveted thereto a friction pad of leather, raw-hide or other non-metallic substance suitable for use as a brake shoe.

Since the rivets pass through both the spring arm and pad and are only slightly countersunk or depressed below the surface of the pad, the pad wears down very quickly so as to expose the rivets to contact with the spool with the consequence that such exposed rivets scrape or scratch into the wooden spool-head, thus having a tendency to catch against the spool and produce an excessive and uneven or jerky retardation, thereby preventing the smooth even rotation of the spool under uniform resistance, which is requisite for the proper delivery of the yarn.

Moreover, under prevailing practice, the replacement of a worn pad involved filing or cutting the rivets and boring out new pads for new rivets, as well as the re-riveting operation itself so that the repair or replacement of the pads is as expensive as are entirely new brake elements.

With a view to overcoming these and other practical difficulties experienced with these devices as heretofore constructed, I have provided a new construction of spool-retarding device which utilizes the flexible arm and a friction pad, but which secures them together without rivets or other fastening means that will produce a jerky or uneven retardation when the pad becomes worn and that not only greatly prolongs the life or duration of the pad itself, but renders it easy of application and of withdrawal for reversal or replacement so that nearly the entire thickness of the pad may be utilized to withstand wear, while a new pad may be almost instantly substituted for a worn out pad.

This and other features of the invention will be described in the following specification and will be defined in the claims hereto annexed.

In the accompanying drawings I have illustrated an inexpensive form of embodying the invention, in which:

Figure 1 is a front elevation of one end of a tube-frame showing the spool-retarding device secured to the tube-frame in operative engagement with the head of the yarn-spool.

Figure 2 is a plan view of the flexible arm to which the friction pad is detachably secured.

Figure 3 is an end elevation of the friction pad itself as used in this form of the invention.

The tube frame illustrated in the drawings is of a well known construction and embraces a tubular carrier-bar 1, to which are secured the yarn-guiding tuft tubes 2, and to whose end is secured a suspension spool-bearing bracket 3, carrying a pivotal latch or hook 4, co-acting with the upward extension of the bracket to releasably suspend the tube-frame from the carrier-chains, in the usual fashion.

The yarn-spool 5 has its journal mounted in a bearing ear 6 for rotatable support as

To the top of the carrier-bar 1 is secured a flexible arm 7, preferably of spring steel, having, near its inner end, an aperture for a fastening screw 8, and having, beyond said fastening screw a hook-like tongue 7^a offset from the plane of the adjacent end of the arm so as to hook through an aperture 1^a in the top wall of the carrier-bar of the tube frame. When thus hooked in place the fastening screw is screwed into the top of the carrier-bar, leaving the free end of the carrier-bar in position to press against the head 5^a of the yarn spool.

The outer or free end of the arm 7 is recessed to receive a friction pad so as to form interlocking engagement therewith and yet permit easy removal of the friction pad for replacement or reversal.

In the present form of the invention the recess is formed by slotting the free end of the arm 7 inwardly and forming the opposite sides of the slot with serrated or hook-like teeth 7^b, inclined inwardly so as to facilitate the insertion of the pad and yet counter-act any tendency of the pad to work out of the slot in the reverse direction. As shown in Figure 3, the pad 9 is of considerably greater thickness than the thickness of the arm 7, and is provided on its opposite edge faces with slots 9^a of sufficient width and depth to re-

ceive the serrated teeth 7^b when the pad is driven or forced into the slot from its open end. The pad being made of compressible or somewhat yielding material, such as 5 leather, raw-hide, vulcanized rubber or other suitable material, when forced between the gripping jaws of the arm 7, is slightly indented by the serrations or teeth which thus form an interlocking engagement sufficient to prevent 10 any accidental displacement of the friction pad through service stresses, while at the same time allowing the pad to be withdrawn by means of a pair of pliers for reversal or replacement. As both sides of the pad are 15 made alike, and each side projects considerably beyond the adjacent surface of the brake-arm, it will be seen that as the pad wears down on one side it may be withdrawn and reinserted with its upper and lower faces reversed 20 so as to continue to wear until the pad is worn out which, in like manner, can be withdrawn for replacement of a new pad of similar construction. By this arrangement not only is the uneven or jerky action prevented, 25 due to wearing the pad down to the point where the former rivets engaged the spool, but the life or duration of the pad is greatly prolonged, while the same brake arm may be used indefinitely with new pads without being discarded, as heretofore, when the 30 pad wears out.

What I claim is:

1. A spool-retarding device for a tube-frame embracing a flexible arm adapted to be secured to a tube-frame with its free end normally pressed toward a yarn-spool therein, said arm being slotted inwardly from its free end to form a pad-receiving recess having serrated sides, a non-metallic friction pad having oppositely disposed external grooves for engagement with the serrated interior edges of said recess to retain the pad in its operative position while allowing it to be withdrawn therefrom.
- 45 2. A spool retarding device for a tube frame embracing in its construction a flexible

arm one end of which is adapted to be secured to the top surface of the tube frame carrier bar with its free end turned upward and spring pressed against the opposing head of a 50 yarn carrying spool, said free end being recessed from its outer end inward to form opposed gripping jaws, a non-metallic friction pad forced into said recess between said jaws and interlockingly engaged therewith to prevent accidental removal, while permitting the pad to be released therefrom for replacement or reversal.

3. The combination with a tube frame carrier bar and its overhead yarn spool, of a 60 spool retarding arm of sheet metal, one end of which is adapted to be secured to the top face of the carrier bar with its free end projecting upward against the head of a yarn spool, said free end being recessed inwardly 65 from its outer end to form substantially parallel spring jaws, and a tight fitting pad of non-metallic material whose opposite side edges are grooved to form telescoping and overlapping engagement with said jaws to hold it against accidental displacement, while permitting its instant removal and replacement.

4. The combination with a tubular tube frame carrier bar and its overhead supported 75 yarn spool, a leaf spring arm whose inner end is formed with an offset extension adapted to be inserted through an aperture in the top wall of the carrier bar, an anchoring screw passing through said arm adjacent to said 80 offset end to anchor it firmly to the tube frame, the free end of said arm being recessed to form parallel gripping jaws, and a spool 85 engaging pad tightly inserted between said gripping jaws with its upper and lower surfaces projecting a substantial distance beyond the plane of the surrounding portion of said arm.

In witness whereof, I have subscribed the above specification.

CHARLES LEA.
